UNITED STATES PATENT OFFICE.

SIMON COOPER, OF BROOKLYN, NEW YORK, ASSIGNOR TO COOPER TEA PACKET CO., INC., OF BROOKLYN, NEW YORK, A CORPORATION OF NEW YORK.

TEA BAG.

Application filed March 23, 1921. Serial No. 454,707.

My invention relates to the packeting of materials, such as tea and aims to provide both a simple, inexpensive packet and a practical and convenient method by which the packets may be constructed, filled and sealed.

In the accompanying drawing I have illustrated but one form the invention may take and in this disclosure:

10 Figure 1 is a side elevation of a complete tea packet;

Figure 2 is a plan of the blank from which the bag is made; and

15 Figure 3 is a view of the formed bag ready for filling.

The blanks 5 are of any suitable textile material and are of generally triangular form, "heart-shaped", in the illustration, so that when doubled and folded on a median 20 line 6, extending from the apex to the base, each will form the sides of a pointed bag-like structure (Figure 2).

These side walls are secured together, by means consisting in the illustration, of a 25 row of stitching 7, extending from the apex along and around the meeting edges to a point short of the doubled edge, approximately at 8, so as to leave a filling mouth at 9 (Figure 3). The tea or other material 30 is then entered through this mouth, after which the stitching is continued to close the mouth over the material in the then filled bag.

To provide a suspension cord for the bag 35 the stitching is continued on past the end of the bag as at 10 and I make further use of this extended bit of stitching by continuing it on through the edge of an identification tag or label 11 as indicated at 12.

40 To prevent undue stretching and to give body to the supporting cord I may employ a reinforcement core for the stitching, such as a strand of twine 13, the stitches being cast about, or over and through this core, 45 which may extend along the entire stitched edge of the bag, as shown in Figure 1.

The invention, it will be seen, provides an inexpensive and easily made bag, which can be readily filled either at the time of its 50 manufacture, or later and which is provided with a suitable reinforcement and suspension cord, with attached label.

I claim:

1. A device for extracting essence from

tea leaves or coffee, comprising a strip of 55 textile fabric folded on its center line to form two plies contacting all around their free edges, a line of stitches extending close to and in parallel relation to said free edges for uniting said two plies, the thread of said 60 stitches being carried over the edge of the fabric, said stitches being continued beyond the fabric to form a chain which serves as a suspending means for the device.

2. A device according to claim 1, comprising a tag on the outer end of said chain, the line of stitches being continued beyond said chain and passed through said tag.

3. A packet for tea or other material comprising a symmetrical blank doubled on itself and a row of stitching connecting the entire length of the meeting edges of the blank to provide a completely closed packet, and said row of stitching being continued 70 beyond the blank to provide a supporting 75 cord.

4. A packet for tea or other material comprising a blank folded on itself and a row of stitching connecting the meeting edges 80 of the blank and continued beyond the blank to provide a supporting cord, and a core of reinforced twine stitched in said cord.

5. A packet for tea or other material comprising a blank folded on itself and a row of stitching connecting the meeting edges of the blank and continued beyond the blank to provide a supporting cord, and a core 85 of reinforced twine stitched in said cord and about the meeting edges of the blank.

6. A packet for tea or other material comprising a blank folded on itself and a row of stitching connecting the meeting edges of the blank and continued beyond the blank to provide a supporting cord, and a core 90 of reinforcement twine stitched in said cord and about the meeting edges of the blank, and an identification tag through which the stitching of cord is extended.

7. A device for extracting essence from tea-leaves or coffee, comprising a bag 100 containing the material whose essence is to be extracted, the bag comprising a strip of textile fabric folded to form two plies contacting all around their free edges, a line of stitches extending close to and in parallel relation to said free edges for uniting said two plies, the thread of said stitches being carried over the edge of the fabric, said 105

stitches being continued beyond the fabric to form a chain which serves as a suspending means for the device.

8. A device as set forth in claim 9, in which there is a tag to which the outer end of the chain is attached.

9. A tea bag adapted to be closed by stitching, and a cord formed integral with said stitching joined with the same at a

point adjacent one corner of the bag and 10 extending without and beyond the same.

10. A tea bag having certain of its sides closed by over stitching, such stitching being extended from and beyond one portion of the bag to provide an integral chained cord. 15

In testimony whereof I affix my signature.

SIMON COOPER.
